CLAIM

The ornamental design for a small cell housing cover, as shown and described.

DESCRIPTION

FIG. 1 is a top front perspective view of a small cell housing cover showing our new design.

FIG. 2 is a bottom rear perspective view thereof.

FIG. 3 is a top plan view thereof.

FIG. 4 is a bottom plan view thereof.

FIG. 5 is a left side elevational view thereof.

FIG. 6 is a right side elevational view thereof.

FIG. 7 is a rear elevational view thereof.

FIG. 8 is a front elevational view thereof; and,
FIG. 9 is a perspective view of the small cell housing cover mounted on a streetlight luminaire.

The stippling shown in the drawings is intended to represent approximate three-dimensional contours of the design and is not intended to indicate surface decoration.

The structures and features shown in broken lines in the drawings, including the streetlight luminaire in FIG. 9, are included for the purpose of illustrating unclaimed portions of the small cell housing cover and environmental structure, and form no part of the claimed design.
